UNITED STATES PATENT OFFICE.

GEORGE R. FOLDS, OF CHICAGO, ILLINOIS, ASSIGNOR TO COOK ELECTRIC COMPANY,
OF CHICAGO, ILLINOIS, A CORPORATION OF ILLINOIS.

ELECTRIC FUSE.

Application filed November 20, 1920. Serial No. 425,309.

To all whom it may concern:

Be it known that I, GEORGE R. FOLDS, a citizen of the United States, residing at Chicago, in the county of Cook and State of Illinois, have invented new and useful Improvements in Electric Fuses, of which the following is a full, clear, concise, and exact description, reference being had to the accompanying drawing, forming a part of this specification.

My invention relates to enclosed renewable electric fuses and more particularly to improved electric fuses of the foregoing character in which the chamber containing the fusible element communicates with the outer air through restricted passageways which extend through the end portions of the enclosed fuse. Moreover, by my present invention, I am able to limit the length of the fusible element that is consumed or vaporized at the time of the exploding of the fuse, without employing a specially designed fusible element for this purpose.

The venting in my present enclosed fuse is effected at each end through a tortuous and restricted passageway that is formed in a washer and continues through a portion of the fusible element and a terminal member which, in the present instance, and for the purpose of illustration only, is shown as a knife-blade terminal.

The washer comprising the restricted and tortuous venting passageway is of substantial mass and is disposed closely adjacent to the fusible element or link so that when this link is vaporized the mass of the said washer will serve to quickly cool the resulting vapors and flames. In addition to the cooling effect occasioned by the mass of the washer, the restricted and tortuous passageway for venting the vapors from the fuse precludes any fire or flame from extending exteriorly of the fuse. It is obvious that the venting of the fuse may be effected through means other than the agency of the washer but that if the washer is of substantial mass, it will serve to rapidly cool the gases and vapors at the time of the blowing of the fuse.

An object, therefore, of my invention is to provide a fire-proof enclosed renewable fuse which comprises elements that may be recurrently used, with the exception of the fusible link, and which precludes any fire

or flame from extending exteriorly of the fuse.

Another object of my invention is to provide an economical fuse of the above indicated character which may be readily manufactured and assembled and in which the washers for venting the fuse will be kept substantially free from any clogging deposits that tend to preclude a proper venting of the fuse.

A further object of my invention is to provide a renewable enclosed fuse in which the washers are of substantial mass of metal and positioned in proximity to the fusible element in order that they may serve to rapidly and effectively cool the burning gases and vapors arising from the consumption of the fusible element. In this fashion, the consumed portion of the fusible element is restricted practically to the portion thereof that extends between the two opposed and spaced end faces of the two washers. By this arrangement of parts and because of the nature of the washers I propose using, the fusible element will be only partially consumed.

For a better understanding of the nature and the scope of my invention reference may be had to the following description and the accompanying drawing; in which—

Fig. 1 is a side view, partially in section, of an enclosed renewable fuse embodying a form of my invention;

Fig. 2 is a cross sectional view taken along the line 2—2 of Fig. 1;

Fig. 3 is a cross sectional view taken along the line 3—3 of Fig. 1;

Fig. 4 is a cross sectional view taken along the line 4—4 of Fig. 1;

Fig. 5 is a partially exploded view showing some of the elements comprised in my fuse;

Fig. 6 is a view showing in perspective the two members that comprise the removable washer comprised in my fuse;

Fig. 7 is a cross sectional view showing a modified form of renewable washer, and

Fig. 8 is a cross sectional view taken along the line 8—8 of Fig. 7.

Referring to the drawing, an insulating and enclosing shell 1, in which a fusible link 2 is positioned, is provided at each of its ends with a metal ferrule 3. Each metal ferrule 3 is interiorly threaded to engage the

end portions of the insulating shell 1. The outer end of each ferrule 3 is provided with an annular portion 4 that serves as a seat for a metallic washer 5. The outer surface 5 of the annular portion 4 of each ferrule 3 is exteriorly threaded to engage a cap member 6 that comprises a portion of the terminal structure 7.

It will be observed by referring to Fig. 6 10 that the washer (designated as 5 in Figure 1) comprises a main member 8 and a plug member 9. The main member 8 is shown as being of frusto-conical form and so positioned in the assembled fuse that its apex 15 is directed inwardly. The base of the member 8 is provided with a beveled flange 9^a that is recessed at 10. The flange 9^a in the removable washer 5 (Fig. 1) is positioned upon a seat provided by the annular portion 20 4 of the ferrule 3 and thus a tight joint therebetween is procured so as to substantially eliminate the venting of the fuse between the ferrule 3 and the washer 5.

The member 8 is provided with a central 25 bore 11 which, in the drawing, is shown as a smooth bore. The plug 9, which is exteriorly threaded throughout its entire length and shown for the purpose of illustration only as being provided with a square 30 thread, is fitted in the bore 11 with a drive fit. The inner end of the bore 11 is countersunk as shown at 12 and this countersunk portion 12 opens through the base of the main member 8 through an opening 13. The 35 thread formed upon the plug 9 constitutes a restricted tortuous passageway having the form of a helix that extends through the assembled washer 5. The length or area of the venting path may be controlled by 40 changing the size and pitch of screw thread.

Referring to Fig. 5 it will be observed that the fusible link 2 has each of its end portions rounded as at 14 these portions 14 being curved oppositely with respect to each other. 45 The extreme ends of the portions 14 are bent over to form flat terminals 15 in which holes 16 are punched. The rounded portions 14 of the link 2 are received in the recesses 10 formed in the washer member 8. 50 By reason of the washer member 8 being made of frusto-conical shape of the form shown in the drawing for the purpose of illustration only, the rounded end portions 14 of the link 2 are in close proximity to the 55 washer 5 in the assembled fuse, as shown in Fig. 1.

A crimp 17 formed at each junction of the terminal portion 15 and the rounded end portion 14 of the link 2 serves to 60 establish the continuity of the beveled flange 9^a formed on the main member 8 and, in assembled position, the crimp 17 makes the joint between the annular portion 4 of the ferrule 3 and the washer 5 continuous. The 65 hole 16 formed in the terminal portion 15

of the link 2 registers with the opening 13 formed in the washer 5.

In Fig. 1 the terminal structure 7 comprises the cap 6 that is preferably pressed from a steel punching. The lower edge of 70 the cap is internally threaded at 19 to engage the exterior thread formed on the annular portion 4 of the ferrule 3. A knife-blade terminal 20 is provided with two integral projecting lugs 21 and extends 75 through a central opening of the cap 6. The lugs 21 project through a base plate 22 and a retaining member 22^a, the former being preferably made of copper. The lugs 21 are peened so as to firmly rivet the blade terminal 20 to the base plate 22 and the member 22^a.

A V-shaped notch 23 is cut in the central portion, and at the base, of the knife-blade terminal 20 and registers with an opening 85 24 that is formed in the base plate 22 and the member 22^a. The opening 13 formed at the base of the washer 5 thus communicates with the outer air through the opening 16 in the link 2, the opening 24 in the base plate 22 and the retaining member 22^a and the V-shaped notch 23 in the knife-blade 90 20.

The passageway from the interior of the insulating shell to the outer air is very advantageously terminated by the notch 23. 95 Since the knife-blade terminal member 20 serves to guard this opening thus provided by the notch 23 it is thereby prevented from being clogged by dirt or other foreign matter. The notch 23 furthermore permits the 100 locating of the opening 13 in the washer in a convenient central position even when the terminal members comprising knife-blade portions are used. It will be noted that because of the thickness of the flanges on the cap member 6, as shown in Fig. 1, the notch 23 is precluded from being covered up by any clips or spring members that may be employed to engage with the knife-blade 105 terminals 20 of the fuse.

In order that the knife-blade members 20 may be in proper alignment, a notch 25 is cut in the annular portion 4 of the ferrule 3 as shown in Fig. 5. A properly positioned lug 26 is upset on the periphery of the rim 110 of the base-plate 22 of the terminal structure 7, which lug is adapted to engage the notch 25 when the terminal structure 7 occupies its proper relative position. The cap member 6 which slidingly engages the base plate 22 115 is then screwed down to retain the knife blade 20 in a fixed position.

While I have shown the terminal member 7 as comprising a knife blade 20, it will be apparent that my present fuse is not limited to a knife-blade construction only, inasmuch as other types of fuses may embody my invention, as will be apparent to those skilled in the art.

Referring to Figs. 7 and 8, I have shown 120

the internal bore 11 of the main member 8 of the washer 5 as being provided with a square bottom. The plug 9 has its inner end transversely slotted at 27, which slot is cut 5 sufficiently deep to reach the base of the screw thread formed on the plug 9. The slot 27 is so located that it bridges the opening 13. The tortuous helical passageway formed by the screw thread cut in the plug 10 9 thus communicates with the outer air through the slot 27 and the opening 13.

From the foregoing description, it will be observed that the washer member 5 is of substantial mass and in close mechanical contact 15 with the fusible link 2 throughout a substantial portion of the length of the fuse. The washer 5 being made entirely of metal has high heat conductive and absorptive qualities and thereby tends to readily cool 20 any hot gases or flames coming in contact therewith. Again, the ends of the fusible link, by reason of their being in close proximity to the washers 5, are not likely to vaporize when the fuse is blown because the 25 mass of the washers 5 quickly absorbs the heat affecting the fusible link, and, therefore, protects the ends of said link from vaporizing. At the same time, the restricted 30 and tortuous passageway formed throughout the length of the washer 5 serves to adequately ventilate the fuse and ensure further cooling of the heated vapors and flames. On the blowing of the fuse, the rush of gases 35 and vapors through the tortuous passageway produces a suction action drawing the flames and fire likewise through the passageways. This tends to cool the flames and extinguish them before passing exteriorly of the fuse. However, other means may be 40 provided for the venting of the fuse, the washers in this instance serving only to cool the vapors and thereby limiting the portion of the fusible link that is consumed.

I am able to accomplish these desirable 45 results by means of the washer 5. This is economically constructed by my use of the screw thread formed on the plug 9, which thus provides a helical passageway of considerable length. It will be obvious that the 50 screw thread serving as the venting passageway need not be confined to the plug 9 but one or the other of the opposing faces should, in any event, be threaded to form a tortuous venting path. For the purpose of 55 economical construction, it is however, preferable to construct the washer as illustrated. Although the main member 8 is shown as being of frusto-conical shape, it will be understood that I do not propose to limit the 60 washer to such a construction.

While I have shown and described in detail an embodiment of my invention it is to be understood that I desire only such limitations to be placed thereupon as are required by the state of the prior art and

specifically set forth in the appended claims.

Having thus described my invention what I now claim as new and desire to secure by Letters Patent is:

1. In a renewable electric fuse, a removable washer having a smooth longitudinal bore formed therein, and an exteriorly threaded plug inserted in said bore to furnish a helical venting path through the washer and adjacent to said threaded plug. 70

2. In an enclosed renewable electric fuse, a removable washer having a tortuous venting path therein which is adjacent to a screw thread formed on one of the elements comprising said washer. 80

3. In an enclosed renewable electric fuse, a removable washer comprising a main member, and an auxiliary member, one of the adjacent surfaces between said members having formed thereupon a helical venting path that restricts the venting of the fuse. 85

4. In an enclosed renewable electric fuse, a removable washer of frusto-conical shape having a helical screw-thread path formed 90 therein which serves to vent the interior of the fuse to the outer air. 90

5. In an enclosed renewable electric fuse, a removable washer having a tortuous restricted path formed therein for venting 95 the fuse, said washer being of substantial mass and high heat conductivity adjacent to said tortuous path to ensure the cooling of the vapors and the flames tending to travel along said tortuous path. 100

6. In an enclosed renewable electric fuse, a removable washer comprising a main member having a central bore, and a plug adapted to fit in said bore, the adjacent surfaces of contact between said main member and said plug providing a helical path 105 in the form of a screw thread for restrictively venting the fuse.

7. In an enclosed renewable electric fuse, a removable washer comprising a main 110 member having a smooth longitudinal bore formed therein, and an exteriorly threaded plug inserted in said bore by a drive fit to provide a tortuous path through said washer. 115

8. In an enclosed renewable electric fuse, the combination of a fusible link extending longitudinally of the fuse and having bent-over ends, with washers for severally engaging said link at its ends, each of said 120 washers having an inwardly projecting extension that conforms to the contour of the associated link-end and being provided with a tortuous venting path that extends in said projecting extension for cooling and restricting the flow of gases and flames exteriorly of the fuse. 125

9. In an enclosed renewable electric fuse comprising a shell member, a fusible link, and members within said shell member for 130

severally engaging ends of said link, said end members being severally provided with a restricted tortuous path for venting the fuse and being of substantial mass and high 5 heat conductivity so that the end members serve to sufficiently cool the vapors prior to their exhaust through said venting passageways.

10. In an enclosed renewable electric fuse comprising a shell member, a fusible link, and end members contained within said shell member and in contact with said fusible link, said end members being of substantial mass and of high heat conductivity, 15 a tortuous passageway being formed in said end members for restrictively venting the fuse therethrough.

11. In an enclosed renewable electric fuse comprising an insulating shell member, a 20 fusible link, and end members housed within said insulating shell member and being of substantial mass and of high heat conductivity, a tortuous passageway being formed in each of said end members for restrictively venting the insulating shell member therethrough.

12. An enclosed electric fuse comprising a shell member, and a terminal member engaging the end of said shell member, said terminal member comprising a knife-blade portion joined to a base plate at substantially right angles thereto, said base plate being provided with a vent-hole at its junction with said knife-blade portion and said knife-blade portion being provided with a 25 notch adjacent said vent hole.

13. An electric fuse comprising a shell member, a base plate engaging the end of said shell member, and a knife-blade terminal joined to the outside of said base plate 30 at substantially right angles thereto and centrally thereof, said plate having a central vent-hole and said knife-blade terminal being provided with a notch adjacent to said vent hole.

In witness whereof, I have hereunto subscribed my name.

GEORGE R. FOLDS.
